CONVERSION OF MERCAPTANS

Joseph A. Chenicek, Bensenville, Ill., assignor to Universal Oil Products Company, Des Plaines, Ill., a corporation of Delaware

No Drawing. Application February 15, 1954,
Serial No. 410,445

10 Claims. (Cl. 196—24)

This invention relates to the conversion of mercaptans and more particularly to a novel method of converting mercaptans contained as impurities in petroleum fractions.

Petroleum fractions, either as originally recovered or after conversion in the refinery, generally contain mercaptans. The presence of mercaptans is particularly undesirable in gasoline and other petroleum distillates because of odor, corrosive properties, etc. Various methods have been utilized to remove or convert the mercaptans.

One method utilized for the treatment of petroleum distillates to remove mercaptans entails the use of an alkaline material and particularly an alkali metal hydroxide including sodium hydroxide, potassium hydroxide, etc. Modification of this process comprises the use of a solubilizer including alcohols, phenols, etc. Other methods include the copper sweetening process, doctor sweetening process, etc.

In accordance with the present invention, mercaptans are converted by reacting with a particular type of organic compound. While this method may be utilized for the conversion of mercaptans as such, it is particularly advantageous for use in the treatment of organic substances, including petroleum fractions, in which the mercaptans are present as an undesired impurity.

In a preferred embodiment, a major proportion of the mercaptans are removed from the petroleum distillate by treatment with an alkali metal hydroxide or otherwise, and the remaining small amount of mercaptans, after such treatment, are converted by means of the novel method of the present invention. The major proportion of the mercaptans are readily removed in the processes of the prior art but the final sweetening of the distillate usually is much more difficult. In accordance with the present invention, final sweetening is effected by converting the remaining mercaptans in the manner to be hereinafter set forth in detail.

In one embodiment the present invention relates to a method of converting a mercaptan which comprises reacting the mercaptan with a beta-dialkylamino ketone.

In a specific embodiment the present invention relates to a method of treating a sour petroleum distillate which comprises reacting the mercaptans contained in the distillate with a beta-dimethylamino ketone.

In another specific embodiment the invention relates to a method of sweetening a sour cracked gasoline which comprises reacting the mercaptans contained in said gasoline with beta-dimethylaminopropiophenone.

The beta-dialkylamino ketones may be illustrated by the following general formula:

where R, R₁ and R₂ are hydrocarbon groups.

It is understood that R, R₁ and R₂ may be the same or different. R₁ and R₂ preferably are alkyl groups. In general, it is preferred that these alkyl groups contain

from 1 to 4 carbon atoms each. Illustrative compounds in which R is an alkyl group include methyl beta-dimethylaminoethyl ketone, ethyl beta-dimethylaminoethyl ketone, propyl beta-dimethylaminoethyl ketone, butyl beta-dimethylaminoethyl ketone, amyl beta-dimethylaminoethyl ketone, hexyl beta-dimethylaminoethyl ketone, heptyl beta-dimethylaminoethyl ketone, octyl beta-dimethylaminoethyl ketone, etc., methyl beta-diethylaminoethyl ketone, methyl beta-dipropylaminoethyl ketone, methyl beta-dibutylaminoethyl ketone, etc., methyl beta-dimethylaminopropyl ketone, methyl beta-dimethylaminobutyl ketone, methyl beta-dimethylaminoamyl ketone, methyl beta-dimethylaminohexyl ketone, etc., methyl beta-diethylaminobutyl ketone, methyl beta-diethylaminoamyl ketone, methyl beta-dipropylaminopropyl ketone, methyl beta-dipropylaminobutyl ketone, methyl beta-dipropylaminohexyl ketone, etc., methyl beta-dibutylaminopropyl ketone, methyl beta-diethylaminobutyl ketone, methyl beta-dibutylaminoamyl ketone, methyl beta-dibutylaminohexyl ketone, etc., ethyl beta-dimethylaminopropyl ketone, ethyl beta-dimethylaminobutyl ketone, ethyl beta-dimethylaminoamyl ketone, ethyl beta-dimethylaminohexyl ketone, etc., propyl beta-dimethylaminopropyl ketone, propyl beta-dimethylaminobutyl ketone, propyl beta-dimethylaminoamyl ketone, propyl beta-dimethylaminohexyl ketone, etc., butyl beta-dimethylaminopropyl ketone, butyl beta-dimethylaminobutyl ketone, butyl beta-dimethylaminoamyl ketone, butyl beta-dimethylaminohexyl ketone, etc., amyl beta-dimethylaminopropyl ketone, amyl beta-dimethylaminobutyl ketone, amyl beta-dimethylaminoamyl ketone, amyl beta-dimethylaminohexyl ketone, etc., hexyl beta-dimethylaminopropyl ketone, hexyl beta-dimethylaminobutyl ketone, hexyl beta-dimethylaminoamyl ketone, hexyl beta-dimethylaminohexyl ketone, etc., heptyl beta-dimethylaminopropyl ketone, heptyl beta-dimethylaminobutyl ketone, heptyl beta-dimethylaminoamyl ketone, heptyl beta-dimethylaminohexyl ketone, etc., octyl beta-dimethylaminopropyl ketone, octyl beta-dimethylaminobutyl ketone, octyl beta-dimethylaminoamyl ketone, octyl beta-dimethylaminohexyl ketone, etc.

Illustrative compounds in which R comprises an aryl group include phenyl beta-dimethylaminoethyl ketone (also named beta-dimethylaminopropiophenone), phenyl beta-diethylaminoethyl ketone, phenyl beta-dipropylaminoethyl ketone, phenyl beta-dibutylaminoethyl ketone, etc., phenyl beta-dimethylaminopropyl ketone, phenyl beta-dimethylaminobutyl ketone, phenyl beta-dipropylaminopropyl ketone, phenyl beta-dimethylaminoamyl ketone, phenyl beta-dimethylaminoamyl ketone, phenyl beta-dibutylaminoamyl ketone, etc., phenyl beta-dimethylaminohexyl ketone, phenyl beta-diethylaminohexyl ketone, phenyl beta-dipropylaminohexyl ketone, phenyl beta-dimethylaminobutyl ketone, phenyl beta-dibutylaminobutyl ketone, phenyl beta-dimethylaminopropyl ketone, phenyl beta-dimethylaminobutyl ketone, phenyl beta-dipropylaminobutyl ketone, phenyl beta-dimethylaminoamyl ketone, phenyl beta-dimethylaminoamyl ketone, phenyl beta-dibutylaminoamyl ketone, etc., tolyl beta-dimethylaminoethyl ketone, tolyl beta-diethylaminoethyl ketone, tolyl beta-dipropylaminoethyl ketone, tolyl beta-dibutylaminoethyl ketone, tolyl beta-dimethylaminopropyl ketone, tolyl beta-dipropylaminopropyl ketone, tolyl beta-dimethylaminobutyl ketone, tolyl beta-dibutylaminobutyl ketone, tolyl beta-dimethylaminopropyl ketone, tolyl beta-dimethylaminobutyl ketone, tolyl beta-dipropylaminobutyl ketone, tolyl beta-dimethylaminoamyl ketone, tolyl beta-dimethylaminoamyl ketone, tolyl beta-dibutylaminoamyl ketone, etc., xylyl beta-dimethylaminoethyl ketone, xylyl beta-dimethylaminoamyl ketone, xylyl beta-dibutylaminoethyl ketone, xylyl beta-dimethylaminopropyl ketone, xylyl beta-dimethylaminobutyl ketone, etc., xylyl beta-dimethylaminoamyl ketone, xylyl beta-dibutylaminoethyl ketone, etc., xylyl beta-dimethylaminopropyl ketone, xylyl

beta-diethylaminopropyl ketone, xylol beta-dipropylaminopropyl ketone, xylol beta-dibutylaminopropyl ketone, etc., xylol beta-dimethylaminobutyl ketone, xylol beta-diethylaminobutyl ketone, xylol beta-dipropylaminobutyl ketone, xylol beta-dibutylaminobutyl ketone, etc.

While the embodiments in which R comprises an alkyl or aryl group are preferred, it is understood that R may comprise any other suitable hydrocarbon group. Thus, R may comprise a cycloalkyl group, in which case representative compounds include cyclohexyl beta-dimethylaminooethyl ketone, cyclohexyl beta-diethylaminooethyl ketone, etc., cyclohexyl beta-dimethylaminopropyl ketone, etc., cyclohexyl beta-diethylaminopropyl ketone, etc., cyclohexyl beta-dimethylaminobutyl ketone, cyclohexyl beta-diethylaminobutyl ketone, etc., cyclohexyl beta-dimethylaminooamyl ketone, cyclohexyl beta-diethylaminooamyl ketone, etc., cyclohexyl beta-dimethylaminohexyl ketone, cyclohexyl beta-diethylaminohexyl ketone, etc., cyclobutyl beta-dimethylaminooethyl ketone, cyclobutyl beta-diethylaminooethyl ketone, etc., cyclopropyl beta-dimethylaminooethyl ketone, etc., other hydrocarbon groups represented by R include alkenyl, aralkyl, etc.

While the dialkylamino compounds are preferred, it is understood that in some cases R₁ and R₂ may comprise carbon atoms of a cyclic group as, for example, where R₁ and R₂ are carbon atoms of a pyridine ring, quinoline ring, isoquinoline ring, quinaldine ring, etc., or a pyrrole ring, pyrrolidine ring, pyrrolidine ring, etc. In still another embodiment R may comprise a substituted hydrocarbon group, the substituent containing oxygen, nitrogen and/or sulfur, including heterocyclic rings. However, it is understood that all of these compounds are not necessarily equivalent.

While the novel process of the present invention is particularly applicable to the treatment of sour gasolines including cracked, straight-run and mixtures thereof, it is understood that the present process may be used for the treatment of other hydrocarbon distillates including cracked and/or straight-run kerosene, diesel fuel, mineral oil, lubricating oil, fuel oil, etc. In another embodiment, the present invention may be utilized for the treatment of gaseous fractions containing mercaptans. In still another embodiment the process may be utilized for the treatment of other fractions containing mercaptans and thus may include synthetic fractions formed from starting reactants containing mercaptans, either as an impurity or as the desired reactant.

The concentrations of beta-dialkylamino ketone to be used will depend upon the concentration of mercaptans in the fraction being treated. At least one mol of beta-dialkylamino ketone should be used per mol of mercaptan to be converted. Preferably an excess of beta-dialkylamino ketone is used in order to ensure complete conversion of the mercaptans, and the excess may comprise up to 50 or more molecular proportions of beta-dialkylamino ketone per molecular proportion of mercaptan.

The process of the present invention may be effected in any suitable manner. In one method, the beta-dialkylamino ketone is commingled with the petroleum distillate and the mixture is subjected to refluxing, distillation, etc. The temperature will depend upon the particular fraction being distilled and may range from slightly above atmospheric to 600° F. or more. The distillation may be effected at atmospheric, subatmospheric or superatmospheric pressure which may be up to 1000 pounds per square inch or more. In another embodiment the beta-dialkylamino ketone is commingled with the petroleum distillate and the resultant mixture is passed through suitable mixing devices such as durion mixers, orifices, etc., and then introduced into a storage tank which, when desired, may contain suitable stirring means, such as paddles, etc., to effect further mixing. When treating a gaseous fraction, the gaseous fraction may be passed through a body of the beta-dialkylamino ketone contained

in a suitable reaction vessel. It is understood that any other suitable method for effecting reaction of the beta-dialkylamino ketone with mercaptans may be utilized.

The following examples are introduced to illustrate further the novelty and utility of the present invention but not with the intention of unduly limiting the same.

Example I

The petroleum fraction of this example comprised a catalytically cracked gasoline to which petroleum mercaptans were added. The petroleum mercaptans were obtained by caustic extraction of a sulfur-containing gasoline. The catalytically cracked gasoline containing mercaptans were divided into two equal portions, and a small amount of beta-dimethylaminopropiophenone was added to one portion. Both portions were then separately refluxed for eight hours and the mercaptan content of each fraction was determined.

After refluxing, the portion containing beta-dimethylaminopropiophenone had a mercaptan sulfur content of 0.008% by weight. The other portion, which did not contain the additive, had a mercaptan sulfur content of 0.02% by weight. It will be noted that the beta-dialkylamino ketone served to considerably reduce the mercaptan content of the gasoline.

Example II

Topped crude oil is subjected to non-catalytic thermal cracking by being heated to a temperature of 940° F. in a furnace and passed through a reaction zone and then into a flash zone wherein vapors separate from residuum. The vapors are withdrawn overhead from the flash chamber and are passed into a fractionating column to separate an overhead fraction comprising gas and gasoline. Butyl beta-dimethylaminooethyl ketone is added to the vapors from the flash chamber before passing into the fractionating column. In the fractionating column the beta-dialkylamino ketone will react with the mercaptans and the reaction product will be retained in the bottoms fraction, thereby resulting in an overhead gasoline fraction of reduced mercaptan content.

Example III

Beta-dimethylaminopropiophenone is added to sour kerosene, and the mixture is intimately stirred and allowed to remain in storage at a temperature of 100° F.

Example IV

Cracked gasoline having a mercaptan content of 0.03% by weight may be treated with caustic-methanol solution to reduce the mercaptan content down to about 0.003% by weight. To the thus treated gasoline, beta-dimethylaminopropiophenone is added with intimate stirring and the mixture is sent to storage. This treatment will serve to produce a sweet gasoline.

I claim as my invention:

1. A method of converting a mercaptan which comprises reacting the mercaptan with beta-dialkylamino ketone.
2. A method of converting a mercaptan which comprises reacting the mercaptan with beta-dimethylaminopropiophenone.
3. A method of treating a sour petroleum distillate which comprises reacting the mercaptans contained in said distillate with a beta-dialkylamino ketone.
4. A method of treating a sour petroleum distillate which comprises reacting the mercaptans contained in said distillate with a beta-dimethylamino ketone.
5. A method of treating a sour petroleum distillate which comprises reacting the mercaptans contained in said distillate with a beta-diethylamino ketone.
6. A method of treating a sour petroleum distillate which comprises reacting the mercaptans contained in said distillate with a beta-dipropylamino ketone.
7. A method of treating a sour petroleum distillate

which comprises reacting the mercaptans contained in said distillate with a beta-dibutylamino ketone.

8. A method of sweetening a sour gasoline which comprises reacting the mercaptans contained in said gasoline with a beta-dialkylamino ketone.

9. A method of sweetening a sour gasoline which comprises reacting the mercaptans contained in said gasoline with beta-dimethylaminopropiophenone.

10. A method of sweetening a sour gasoline which comprises reacting the mercaptans contained in said gasoline 10 with an alkyl beta-dimethylaminoethyl ketone.
